WINDOW SHADE ATTACHMENT

Arthur H. Cadieux, Granby, Quebec, Canada

Application February 24, 1944, Serial No. 523,706

3 Claims. (Cl. 160—102)

This invention relates to a window shade attachment which may be easily applied to a shade now in use or to a shade in the course of manufacture or to one at the time of the sale of the shade.

The primary object of the invention is the provision of a device which will improve the appearance of a shade and will cause the shade to hang better from its roller and provide a medium which a person may grip in adjusting the shade and will more evenly distribute the operating strains over the shade to prevent tearing thereof and in some instances may be made to act as a ventilator to an open window when the shade is drawn.

With these and other objects in view as will become more apparent as the description proceeds, the invention consists in certain novel features of construction, combination and arrangement of parts as will be hereinafter more fully described and claimed.

For a complete understanding of my invention, reference is to be had to the following description and accompanying drawing, in which

Figure 1 is a front elevation illustrating a window carrying a shade equipped with an attachment constructed in accordance with my invention.

Figure 2 is a fragmentary transverse sectional view showing the window partly open with the shade drawn and the attachment acting as a ventilator.

Figure 3 is a fragmentary perspective view illustrating a modified form of my invention.

Referring in detail to the drawing, the numeral 5 indicates a window, 6 a shade of a conventional construction supported on a roller 7. The shade 6 is equipped with an attachment 8 constructed in accordance with the present invention, which attachment can be easily and quickly applied to the shade and will provide for the better hanging of the shade from the roller by providing weight thereon as well as improving the general appearance of the shade as well as the window. The attachment also may act as a ventilator when the shade is drawn and the window partly open, as clearly shown in Figure 2. Further, the attachment will provide a medium which a person may grasp in operating the shade to raise and lower the latter and will distribute the operating strains over the shade in such a way as to be less apt to damage or tear the shade.

The attachment is in the form of an elongated frame 9, the length of which is approximately the width of the shade and has secured to the

upper edge thereof an attaching medium 10 of substantially triangular shape in cross section with a slot extending the full length thereof and within the apex of the medium 10. The medium 10 is open at both ends which will permit the hemmed end of the shade, carrying the usual stick 11, to be inserted in the medium 10 from either end thereof with the shade extending through the slot thereby firmly attaching the frame 9 on the shade. The frame 9 has arranged therein a plurality of inclined slats 12 through which air may pass for ventilating purposes when the window is in partly open position, as shown in Figure 2.

15 The attachment when applied to the shade will place weight thereon so that the shade will hang better from its roller 7 and remain in a straight depending position within the window frame under normal conditions. The attachment also 20 will provide an improved appearance to the shade as well as permitting air to pass through the window should the latter be in an open position.

Referring to my modified form of the invention, 25 the attachment is indicated by the character 13 and consists of a panel 14 having formed on one longitudinal edge thereof an attaching medium 15 similar in construction to the attaching medium 10. The panel 14 takes the place of the frame 9 and the slats 12 and when applied to the shade will weight the latter and give the shade a better appearance besides providing a medium which a person may grasp in the adjustment of the shade. The panel 14 as well as the medium 30 35 40 45 50 55 15 may be constructed of transparent material, preferably of a plastic character which also applies to the attachment 8 shown in Figures 1 and 2. The panel 14 being of transparent plastic quality will allow a certain amount of light to pass therethrough and may be made to harmonize with the color or general appearance of the shade.

While I have shown and described the preferred embodiment of my invention, it is to be understood that minor changes in construction, combination and arrangement of parts may be made without departing from the spirit and scope of the invention as claimed.

Having thus described my invention, what I claim is:

50 1. In a shade attachment, a rigid member having a length substantially equal to the width of a shade, a channel member having converging upper edges on said rigid member to slidably receive and grip a shade at the free end of the latter, said rigid member being of frame-like con-

struction below the channel member and including a plurality of spaced inclined slats.

2. In a shade attachment, a rigid semi-transparent panel having a length substantially equal to the width of a shade, and an attaching medium forming a part of the upper edge of the panel to receive and grip the free end of a shade, said attaching medium comprising a channel shaped member open on at least one end to slidably receive the free end of the shade, said channel shaped member having converging upper edges.

3. In a window shade attachment, a rigid member having a length substantially equal to the width of a shade and arranged and adapted for

releasable attachment along the bottom edge portion of the shade to serve the dual function of a sustaining weight for the shade and a ventilating cover for the opening under a raised window sash, and an elongated attaching medium secured to the top of said rigid member and being of substantially triangular channel shape in cross section and open at each end, said attaching medium having a restricted slot extending longitudinally at its top from each end along the apex thereof and defined by convergent side walls of the member.

ARTHUR H. CADIEUX.
